UNITED STATES PATENT OFFICE

HENRY W. THAYER, OF NEW YORK, N. Y.

EXPLOSION-ENGINE.

1,299,264.

Specification of Letters Patent.

Patented Apr. 1, 1919.

Application filed April 4, 1916. Serial No. 88,891.

To all whom it may concern:

Be it known that I, HENRY W. THAYER, a citizen of the United States of America, and a resident of the city, county, and State of New York, have invented a new and useful Improvement in Explosion-Engines, which invention is fully set forth in the following specification.

This invention relates to internal combustion engines, and more particularly to an improved valve mechanism for controlling the intake of the explosive mixture and the exhaust of the burnt gases.

The primary object of this invention is to provide a valve mechanism which will control the intake of the explosive mixture, permit the compression and explosion of such mixture, and provide for the complete exhaustion of the burnt gases, in the most efficient and effective manner, whereby the engine may operate with increased efficiency over those heretofore known to the art.

A further object is the provision of a valve mechanism which will open substantially instantaneously, remain open throughout the period of intake or exhaust, as the case may be, and then close substantially instantaneously and remain closed throughout the compression and explosion of the explosive mixture.

Another object is to provide a valve mechanism which will offer less resistance to its actuation than those heretofore employed, avoiding the necessity of overcoming the back-pressure incident to the use of the commonly employed puppet valves, and obviating the necessity for valve-seating springs with the consequent loss of work in opening the valves against the resistance of such springs.

Yet another object is to provide a valve mechanism with a fewer number of parts than heretofore employed, and thereby to obtain a decrease in the weight of the engine without interfering with its efficiency or working capacity—a consideration which becomes of importance in the provision of engines for automobiles, and of very great importance in the provision of engines for use on aeroplanes.

A still further object is to provide such a construction of valve mechanism as will admit of the valve members being properly cooled at all times so as to insure against overheating of any part thereof.

Other objects reside in the provision of a

valve mechanism which will wear to a less extent than those heretofore used, which will avoid smutting and pitting of the valve members, which may be assembled, fitted and adjusted easily, which may be overhauled and repaired readily, and which will be accessible at all times for purposes of inspection.

Broadly, the invention comprises the provision of a plurality of relatively-rotatable and intermittently-actuated valve members, each provided with ports which may be brought into register with one another and with the admission or exhaust port of the engine cylinder, as the case may be. Preferably, though not necessarily, separate valve mechanisms of this type are provided for the intake and for the exhaust.

A practical and preferred embodiment of the invention comprises, both for the intake and for the exhaust of the engine, two differentially-movable, intermittently-actuated rotary valve sleeves, one within the other and both within a cylindrical valve casing, both of said sleeves and said valve casing being provided with ports which are at the proper times brought into register for the admission of the explosive mixture or the exhaust of the burnt gases, as the case may be; and means actuated from the crank-shaft and connected to said sleeves for rotating said sleeves in the same direction at different speeds in a step-by-step movement.

The invention is capable of receiving a variety of mechanical expressions, one of which has been selected for purposes of illustration in the accompanying drawings, but it is to be expressly understood that the embodiment there shown is for purposes of illustration only, and is not designed as a definition of the limits of the invention, reference being had to the appended claims for such purpose.

In the drawings, wherein the same characters of reference indicate the same parts throughout the several views,

Figure 1 is a vertical section of the engine on the line 1—1 of Fig. 2, showing the valve-actuating mechanism in dotted lines;

Fig. 2 is a horizontal section of the valve mechanism on the line 2—2 of Fig. 1;

Fig. 3 is a fragmentary vertical section of the engine on the line 3—3 of Fig. 1, showing the valve-actuating mechanism in elevation;

Fig. 4 is a diagrammatic view of the successive positions of the valve sleeves owing to the successive intermittent movements of the valve-actuating mechanism; and
5 Fig. 5 is a detail of the two-armed tripping crank.

Referring in detail to the drawings, 1 is the crank-shaft of the usual or any preferred form of internal combustion engine, 10 preferably of the four-cycle type. 2 is the usual crank connected by means of crank-pin 3 with the pitman 4 which is pivotally connected at 5 to the piston 6. Piston 6 reciprocates in the usual manner in cylinder 7, 15 which may be water-jacketed as indicated at 8. At the upper end of the cylinder is the usual firing chamber in the cylinder head, as indicated at 9, provision being made for the spark-plug at 10. While the invention is 20 shown as embodied in an engine employing vertical cylinders, it is to be expressly understood that it is not restricted in its application to an engine of this type. Any desired number of cylinders may be used, an engine 25 employing three or more cylinders being indicated in Fig. 2, but for convenience of description reference has been made to but one cylinder in the course of the above explanation.

30 Extending horizontally above the cylinder or cylinders, throughout the length of the bank or block of cylinders, is a pair of valve casings 11 and 12. These valve casings are preferably cylindrical and positioned one on 35 each side of the plane of the axes of the cylinders, the one on the right of Fig. 1 being chosen for the purpose of this description as the intake-valve casing, and that on the left as the exhaust-valve casing. Each of these 40 casings is provided with a series of ports 13, each communicating with the interior of a cylinder, and with a corresponding number of diametrically opposed ports 14 communicating with the intake or the exhaust-manifold, as the case may be. Mounted within 45 each of these valve casings are two nested, coaxial cylindrical valve members or sleeves 16 and 17, each of these sleeves extending the full length of the bank or block of cylinders. 50 Each of the inner sleeves is divided by transverse partitions into as many chambers as there are cylinders, and each chamber is provided with diametrically opposed ports 19. Each of the outer sleeves is provided with a 55 series of diametrically opposed ports 18, one pair for each cylinder, adapted to register at the proper time with the casing and inner-sleeve ports. As shown, the ports in the inner sleeves are materially larger than the 60 ports in the outer sleeves and in the casings. The valve casings are preferably water-jacketed, as shown at 20.

For rotatably mounting and actuating these valve members, a variety of different 65 constructions may be employed, but the pre-

ferred construction is that illustrated in the drawings, wherein each of the inner valve sleeves 17 is secured at one end, as by means of a screw-thread connection, on the flanged head 21 of a spindle 22 which is rotatably mounted at its outer end by engagement in a recess therein of a set screw 23. The opposite end of each sleeve 17 is rotatably mounted by engagement of a set screw 24 in a recess in an end-piece 25, which may be screw-threaded within the corresponding end of said valve sleeve. Lock nuts 26 are preferably provided to hold the set screws in adjusted position. Each of the outer valve sleeves 16 is rotatably mounted upon the exterior cylindrical surface of the corresponding inner valve sleeve 17, and in snug rotary engagement with the inner cylindrical surface of the corresponding valve cylinder. For rotating the valve sleeves a sprocket 27 85 is keyed upon each spindle 22, and a sprocket 28 is mounted to rotate freely upon each spindle 22, each sprocket 28 being connected, preferably integrally, with a sleeve 29 secured, as by a screw-thread connection at 30, 90 with the corresponding outer valve sleeve 16. Sprockets 27 and 28 are preferably of the same diameter.

In the crank-pit, but preferably above and shown as in vertical alinement with the 95 crank-shaft 1, is a stub shaft 31 carrying sprockets 32 and 33 which are keyed to rotate as a unit thereon. Preferably sprocket 32 is larger than sprocket 33, and its diameter should be a multiple of the diameter of 100 sprocket 33. In the preferred embodiment, sprocket 32 is three times the diameter of sprocket 33. Sprocket 32 is connected, as by a chain 34, with sprockets 27, and sprocket 33 is connected, as by a chain 35, with sprockets 105 28. Chain 34 passes under sprocket 32 and over both sprockets 27, whereby both of the outer valve sleeves are driven by the sprocket 32 in the same direction and at the same speed. Chain 35 passes under sprocket 33 and over 110 both sprockets 28, whereby both of the outer valve sleeves are driven by the sprocket 33 in the same direction and at the same speed. For rotating sprockets 32 and 33, a star 115 wheel 36, shown as provided with eight radially extending teeth, is mounted on stub shaft 31 in keyed relation with said sprockets 32 and 33. For turning the star wheel 36, a two-armed tripping crank 37, carrying at either end pins 38 and 39 whereon are 120 mounted rollers 40 and 41 respectively, is keyed on the crank-shaft 1 directly beneath the star wheel 36.

Operation: At each half revolution of the crank-shaft 1, one of the rollers 40 and 41 125 upon the two-armed tripping crank 37 will come into engagement with one of the teeth of star wheel 36, and advance such star wheel in a step-by-step rotation through 45° or one-eighth of a revolution. Rotation of 130

the star wheel 36 will produce a corresponding rotation of sprockets 32 and 33 keyed thereto. As these two sprockets are keyed to move as a unit, they will have the same speed of rotation. Sprockets 27 and 28, connected to sprockets 32 and 33 by the chains 34 and 35 respectively, will be correspondingly advanced by the rotation of said sprockets 32 and 33. As sprockets 28 are preferably of the same diameter as sprocket 32, for each one-eighth revolution of the star wheel 36 sprockets 28 will each be likewise advanced one-eighth of a revolution. As, however, sprocket 32 is preferably three times the diameter of sprocket 33, while sprockets 27 are preferably of the same diameter as sprockets 28, sprockets 27 will each be advanced a distance three times as great as that of each sprocket 28, that is, through three-eighths of a revolution. As the sprockets 27 and 28 are connected respectively with the inner and outer sleeves 17 and 16 of the valve mechanism, at each actuation of the star wheel each outer sleeve 16 will be advanced one-eighth of a revolution, while each inner sleeve 17 will be advanced three-eighths of a revolution, the inner and outer sleeves in each of the valve casings moving in the same direction in a step-by-step rotation.

Assume now that the valve sleeves are in the position represented at A in Fig. 4, and that the valve mechanism at the right is for the intake of the explosive mixture, and that the valve mechanism at the left is for the exhaust of the burnt gases. At the intake side the ports of both sleeves and of the valve casing are in register, these ports being entirely open for the admission of the explosive mixture throughout the downward stroke of the piston. The ports of the exhaust valve sleeves are not only out of register with each other, but out of register with the ports of the corresponding valve casing. Approximately at the end of the downward stroke of the piston, the star wheel will be advanced one-eighth of a revolution by engagement therewith of one of the rollers on the two-armed tripping crank. Both sleeves of the intake valve thereupon will be substantially instantaneously moved, their ports moving out of register with each other and with the ports of the valve casing; and both sleeves of the exhaust valve will be correspondingly advanced, the valve sleeves of both valves then assuming the positions indicated at B. These positions will be maintained throughout the compression stroke of the piston. Approximately at the end of this stroke a second tooth on the star wheel will be engaged and advanced, and the valve sleeves will be correspondingly advanced to the positions indicated at C. These positions will be maintained throughout the explosion or expansion stroke of the

piston. Approximately at the end of the latter stroke of the piston, a third tooth of the star wheel will be engaged and advanced, whereby the valve sleeves will be advanced to the positions indicated at D. Now the ports through the sleeves of the exhaust valve are in register with each other and with the ports on the exhaust-valve casing, they coming into register substantially instantaneously and remaining wide open throughout the exhaust stroke of the piston. During this period the admission valve is closed, as shown at the right at D. Approximately at the end of the exhaust stroke, a fourth tooth will be engaged and advanced, and the valve sleeves will be advanced to the positions indicated at E. As here seen, the ports of the intake-valve sleeves and valve casing are in register, which wide-opened position they assume substantially instantaneously and will retain throughout the suction stroke of the piston, the exhaust-valve sleeves being in the position shown at the left at E. Upon the next two advances of the star wheel, the valves will successively assume the positions indicated at F, for the compression stroke, and at G for the explosion or expansion stroke. When the seventh tooth of the star wheel is engaged and advanced, the valves will then assume the positions shown at H, which positions they will maintain throughout the exhaust stroke. Upon the eighth and last tooth of the star wheel being engaged and advanced, the valves will assume substantially instantaneously the positions indicated at A, closing the exhaust and opening the admission ports. The cycle will then be repeated.

While the description of operation has proceeded as if there were but one cylinder, it will be understood that any desired number of cylinders may be used, the cranks connected with the corresponding pistons being in proper angular relation according to the usual practice, and the ports in the sleeves of both the intake and the exhaust valves being properly located for each cylinder to admit the explosive mixture and permit the exhaust of the burnt gases in proper timed relation with such events in the cycles of other cylinders.

It will be clear from the above detailed description that a valve mechanism has been obtained for both the intake and the exhaust which opens and closes its ports substantially instantaneously, which maintains its ports entirely open throughout one of the four strokes of the piston, and which maintains its ports entirely closed throughout the next three succeeding strokes of the piston. Thereby all of the advantages of the generally used puppet valve are obtained, but without the defects inherent in the construction of such valve.

It will also be apparent that the outer sleeve of each valve mechanism is in continuous engagement with the water-cooled valve casing, that but one-eighth of its surface is exposed to the interior of the cylinder at any one time, and that any one portion of the outer sleeve is returned to exposure to the interior of the cylinder only after eight actuations of the star wheel, or 10 four revolutions of the crank-shaft. Therefore, for seven-eighths of the time, each portion of this outer sleeve is efficiently cooled, and for only one-eighth of the time is it exposed to the hot gases. It will also be apparent 15 that inasmuch as the inner sleeve is never exposed to the heat of the explosion, and is in communication with the interior of the cylinder only after each four actuations of the star wheel, while it is in continuous engagement with the cooled outer sleeve, the inner sleeve never becomes overheated.

It will also appear that by the provision of intermittently-actuated and differentially-rotatable valve sleeves, there is a very considerable reduction in the number of moving parts, and a very material decrease in the loss of efficiency owing to the frictional resistance opposed to the movement of such parts; that to actuate this valve mechanism, 20 the necessity of overcoming back-pressure and the resistance of valve-seating springs is avoided; that the rotary engagement of the parts will scrape off any particles of carbon that may adhere thereto, and thereby prevent smutting; that the parts of the valve mechanism are not exposed to excessive heat and to high heat only for very short periods, whereby there is little likelihood of pitting; that the nature of the engagement 25 of the parts during movement is such as to cause little wear thereof; that the reduction of the number of parts enables an engine to be obtained of less weight than heretofore obtained; and that the absence of 30 complicated parts renders the engine easily assembled, fitted and adjusted, and readily inspected and repaired.

While the above embodiment has been described with considerable particularity, it is 35 to be expressly understood that the invention is susceptible of embodiment in a variety of forms, some of which will readily suggest themselves to those skilled in the art, and that the above detailed description is 40 not to be taken as a definition of the scope of the invention, reference being had to the appended claims for that purpose.

What is claimed is:—

1. The combination with the cylinder of 45 an internal-combustion engine, of a valve-casing having a port communicating with said cylinder, a plurality of concentric rotary valve-members located in said casing and provided with diametric ports adapted 50 to register with each other and with said

casing-port, and means intermittently moving said valve-members in the same direction but at different speeds respectively.

2. The combination with the cylinder of 55 an internal-combustion engine, of a valve-casing having a port communicating with said cylinder, a plurality of concentric rotary valve-members located in said casing and provided with diametric ports adapted 60 to register with each other and with said casing-port, and means intermittently moving said valve-members in the same direction but at different speeds respectively, the ports of the more-rapidly driven member being 65 larger circumferentially than the other ports. 70

3. The combination with the cylinder of 75 an internal-combustion engine, of two separate valve-casings each having a port communicating with said cylinder for inlet and for exhaust respectively, a plurality of concentric rotary valve-members located in each 80 casing and each provided with a diametric port adapted to register with each other and with their own casing-port, and intermittently-acting means for moving the valve-members of each set in the same direction but at different speeds respectively.

4. The combination with the cylinder of 85 an internal-combustion engine, of two separate valve-casings each having a port communicating with said cylinder for inlet and for exhaust respectively, a plurality of concentric rotary valve-members located in each 90 casing and each provided with a diametric port adapted to register with each other and with their own casing-port, and intermittently-acting means for moving the valve-members of each set in the same direction but at different speeds respectively, the ports of the more-rapidly driven members being 95 larger circumferentially than the other ports. 100

5. In an internal-combustion engine, in combination with a cylinder, piston and crank-shaft thereof, a valve casing having a port communicating with said cylinder, rotary valve members therein provided with 105 ports, and means to differentially and intermittently rotate said valve members comprising a star wheel, sprockets of different diameter connected to rotate with said star wheel, connections between said sprockets and said valve members respectively, and means on said crank-shaft to rotate said star wheel step-by-step.

6. In an internal-combustion engine, in 110 combination with a cylinder, piston and crank-shaft thereof, a valve casing having a port communicating with said cylinder, rotary valve members therein provided with 115 ports, means to relatively and intermittently rotate said valve members in the same direction comprising a star wheel, sprockets connected to rotate with said star wheel, sprockets coaxial with said valve members, driving connections between said first-mentioned and 120 125 130 135

said second-mentioned sprockets respectively, and means on said crank-shaft to rotate said star wheel step-by-step.

7. In an internal-combustion engine, in combination with a cylinder, piston and crank-shaft thereof, separate intake and exhaust-valve casings having ports communicating with said cylinder, inner and outer rotary valve members provided with ports in each of said casings, and means to intermittently rotate said valve members comprising a star wheel, means on said crank-shaft for rotating said star wheel step-by-step, a common driving connection with said star wheel for both of said inner valve members, and a common driving connection with said star wheel for both of said outer valve members.

8. In an internal-combustion engine, in combination with a cylinder thereof, a valve mechanism comprising a valve casing having a port communicating with said cylinder, inner and outer valve members therein provided with ports adapted to register with said casing port, and means rotating said members at different speeds in the same direction, said inner member having the greater speed of rotation and said inner member port being larger circumferentially than said casing port.

9. In an internal-combustion engine, in combination with a cylinder thereof, a valve mechanism comprising a valve casing having a port communicating with said cylinder, inner and outer valve members therein provided with ports adapted to register with said casing port, and means intermittently rotating said members at different speeds in the same direction, said inner member having the greater speed of rotation and said inner member port being larger circumferentially than said casing port.

10. In an internal-combustion engine, in combination with a cylinder thereof, a valve mechanism comprising a valve casing having a port communicating with said cylinder, inner and outer valve members therein provided with ports adapted to register with said casing port, and means rotating said members at different speeds, said inner member having the greater speed of rotation and said inner member port being larger circumferentially than said outer member port and said casing port.

11. In an internal-combustion engine, the combination with the cylinder, the piston, and the main shaft, of two cylindrical valve-

casings each having two ports affording a transverse passageway through said casing and into or out of said cylinder, a sleeve-valve rotatable in each casing and having two transverse ports corresponding to and adapted to register with said casing-ports, a cylinder-valve rotatable in each sleeve and having a transverse port corresponding to 60 and adapted to register with the other ports aforesaid but of greater dimensions circumferentially of said cylinder-valve, and means actuated by said shaft for intermittently rotating said sleeve-valves and simultaneously 65 rotating said cylinder-valves in the same direction but at greater speed.

12. In an internal-combustion engine, the combination with the cylinder, the piston, and the main shaft, of a cylindrical valve-casing having two ports affording a transverse passageway through said casing and into or out of said cylinder, a sleeve-valve rotatable in said casing and having two transverse ports corresponding to and adapted to register with said casing-ports, a sleeve-valve rotatable in said sleeve and having a transverse port corresponding to and adapted to register with the other ports aforesaid but of greater dimensions circumferentially of said cylinder-valve, and means actuated by said shaft for intermittently rotating said sleeve-valve and simultaneously 70 rotating said cylinder-valve in the same direction but at a greater speed.

13. In a four-cycle internal-combustion engine, the combination with the cylinder, the piston, and the main shaft, of a cylindrical valve-casing having two ports affording a transverse passageway through said casing and into or out of said cylinder, a sleeve-valve rotatable in said casing and having two transverse ports corresponding to and adapted to register with said casing-ports, a cylinder-valve rotatable in said sleeve and having a transverse port corresponding to 95 and adapted to register with the other ports aforesaid but of twice the width circumferentially of said cylinder-valve, and means actuated by said shaft for 100 intermittently advancing said sleeve-valve one-eighth of its complete revolution for each one-half revolution of said shaft while simultaneously advancing said cylinder-valve three times as fast in the same direction.

In testimony whereof I have signed this specification.

HENRY W. THAYER.
